CLAIM

The ornamental design for a housing for an electrical connector, as shown and described.

DESCRIPTION

FIG. 1 is a perspective view of a housing for an electrical connector showing our new design;

FIG. 2 is a front elevational view thereof;

FIG. 3 is a right elevational view thereof, the left elevational view being a mirror image;

FIG. 4 is a top plan view thereof;

FIG. 5 is a bottom plan view thereof;

FIG. 6 is a rear elevational view thereof; and

FIG. 7 is a section view thereof taken at cut line 7—7 in FIG. 2.

FIG 1**FIG 4****FIG 2****FIG 3**

FIG 5**FIG 6****FIG 7**
